CLAIM

The ornamental design of an access point antenna housing, as shown and described.

DESCRIPTION

FIG. 1 is a front isometric view of an access point antenna housing.

FIG. 2 is a back isometric view of the access point antenna housing of FIG. 1.

FIG. 3 is a front view of the access point antenna housing of FIG. 1.

FIG. 4 is a right side view of the access point antenna housing of FIG. 1.

FIG. 5 is a back view of the access point antenna housing of FIG. 1.

FIG. 6 is left side view of the access point antenna housing of FIG. 1.

FIG. 7 is a top view of the access point antenna housing of FIG. 1.

FIG. 8 is a bottom view of the access point antenna housing of FIG. 1.

FIG. 9 is another front isometric view of the access point antenna housing of FIG. 1; and,

FIG. 10 is another back isometric view of the access point antenna housing of FIG. 1.

The broken lines illustrate environmental structure of the access point antenna housing and form no part of the claimed design.
